J. A. SCHARWATH,
INSULATING MATERIAL,
APPLICATION FILED JAN. 15, 1916.

1,318,463.

Patented Oct. 14, 1919.

UNITED STATES PATENT OFFICE.

JOHN A. SCHARWATH, OF ELIZABETH, NEW JERSEY.

INSULATING MATERIAL.

1,318,463.

Specification of Letters Patent. Patented Oct. 14, 1919.

Application filed January 15, 1916. Serial No. 72,197.

To all whom it may concern:

Be it known that I, JOHN A. SCHARWATH, a citizen of the United States of America, and a resident of Elizabeth, county of Union, 5 and State of New Jersey, have invented certain new and useful Improvements in Insulating Materials, of which the following is a specification, reference being had to the accompanying drawings, forming a part 10 thereof.

My invention relates to materials for insulating against the transfer of heat and has special reference to such as is adapted for use in a conduit or similar structure for the 15 protection of steam and hot water pipes, or of pipes containing refrigerating liquids against the transfer of heat from or to the pipes.

One object of my invention is to provide a 20 relatively inexpensive and efficient heat insulating material that shall be impervious to or uninjured by moisture and which shall be capable of resisting heat at relatively high temperatures without injury. 25 Other objects and advantages of my invention will be set forth hereinafter, and in order that my invention may be thoroughly understood I will now proceed to describe the same in the following specification, and 30 then point out the novel features thereof in appended claims.

Referring to the drawings:

Figure 1 is a transverse elevation of a conduit, a part of which has a filling of an insulating material which is made according to 35 and is an embodiment of my invention.

Fig. 2 is a sectional elevation on a larger scale of one of the particles of the novel insulating material.

40 The conduit illustrated is particularly adapted for use under ground, to provide a protective casing for pipes transmitting steam, hot water, or refrigerated liquids, or in fact any fluid which it is desired to maintain at a temperature either greater or less than the temperature of the surrounding earth.

As clearly shown in Fig. 2, the conduit is 45 built up of hollow bricks or tiles, which extend longitudinally and have one or more longitudinally extending holes or pockets. At the bottom of the conduit are corner tiles or bricks 11 and 12 and intermediate tiles 13 and 14. The number of intermediate tiles 55 will of course depend on the size of the conduit. The side walls are built up on the cor-

ner bricks 11 and 12, and comprise tiles 15—17 and 16—18. At the top are corner tiles 19 and 20 and intermediate tiles 21 and 22.

Obviously the number of tiles interposed between the corners may be increased indefinitely depending upon the size of the tile or bricks of which the conduit is constructed. Each of the bottom row of bricks 11, 12, 13 65 and 14 is provided with a transverse web 23 which divides the opening into a lower chamber 24 and an upper chamber 25. Some of the chambers in the hollow bricks or tiles are filled with insulating material 70 indicated at 26.

It will be observed that the conduit and insulating materials of my invention are particularly arranged and adapted for the protection of steam pipes and the like, since 75 special provision is made in every case against the corroding influence of moisture.

The bricks 15, 16, 17 and 18 constituting the side walls are provided with lateral projections 32—33 which extend inwardly and 80 constitute notched brackets which form supports in which short lengths of pipe or rod, indicated at 35, may be supported in a transverse position and constitute rollers or hangers for steam pipes 36 or whatever may 85 be carried in the conduit.

If ordinary insulating materials are utilized within the conduit to fill in the space between the pipes and conduit, they are likely to absorb moisture. This feature has 90 been particularly troublesome hitherto when steam heating pipes were laid in conduits and were only utilized for transmitting steam during a few months of the year, the insulating material or filler around the pipe, 95 such as, for example, mineral wool, magnesia, asbestos fiber, infusorial earth, or combinations of these materials, by reason of their porous nature would absorb and hold a large quantity of moisture and act in 100 effect like a wet sponge held against the piping. Thus the pipes were rapidly corroded and destroyed during the summer months, and, furthermore, the insulation was rendered practically valueless.

105 If insulating material, such as cork, for example, is employed in order to avoid the aforesaid difficulties, on account of moisture, a new factor of trouble is introduced on account of the fact that the cork is charred 110 by the heat and rendered hydroscopic and subject to the same difficulty.

According to my present invention I prefer to utilize within the conduit directly surrounding the steam pipes, for example, a quantity of small insulating bodies 40, 5 which may for example, correspond in size to pea coal, each body consisting of a small piece of cork 41 of irregular shape having an envelop or coating 42 of concrete and plaster for example, and by reason of this 10 heat protective coating the cork is enabled to resist relatively high temperatures even though the thickness of the envelop or coating is comparatively small, $1\frac{1}{16}$ " for example. These coated bodies which have the 15 appearance of small pebbles are filled into the space in the conduit around the pipes.

A mass of small solid bodies as above described, will not absorb and hold moisture like a sponge but will permit liquid to flow downwardly through the mass.

20

What I claim is:

1. An insulating granular mass consisting of small non-adhering bodies or particles, of broken insulation each having a coating or jacket of cement formed thereon.

25

2. An insulating granular mass consisting of small non-adhering bodies or particles of broken cork, each having a coating or jacket of cement formed thereon.

In witness whereof I have hereunto set 30
my hand this 12th day of January, 1916.

JOHN A. SCHARWATH.
